UNITED STATES PATENT OFFICE

2,513,973

CATSUP DISPENSER

Guy W. Stott, Huntington Park, Calif.

Application August 3, 1946, Serial No. 688,203

4 Claims. (Cl. 215—3)

1

This invention is a dispenser for dispensing catsup and the like.

The general object of the invention is to provide a dispenser by means of which catsup and the like may be positively pumped out of a container for use.

A more particular object is to provide a dispenser of the character stated, which may be applied to a conventional catsup bottle for pumping catsup from said bottle upon foods, as and when needed by persons while eating.

Other objects and advantages will appear hereinafter as this specification progresses.

The invention is illustrated in the annexed drawing which forms a part of this specification and in which:

Fig. 1 is a vertical longitudinal section of my dispenser and a catsup bottle in which my dispenser is mounted.

Fig. 2 is an enlarged fragmentary vertical section of my dispenser pump piston and cylinder.

Fig. 3 is an enlarged fragmentary vertical section of the lower end of the pump cylinder and the intake valve of said cylinder.

Referring more particularly to the drawing, in which corresponding parts are designated by the same reference numerals in all of the figures, my invention comprises a pump designated 1 in its entirety, which includes an elongated tubular barrel 2 constructed with an intake valve 3 in its lower end, a spout 4 at its upper end and a bottle cap 5 near the lower end of said spout; a reciprocative valved piston 6 in said barrel, a piston rod 7 extending upwardly from said piston through a head 8 on the upper end of said barrel; a coil spring 9 surrounding said piston rod between said piston and said head; a handle 10 secured on the upper end of said barrel 2 on said head 8; and an actuating lever 11 pivoted at 12 to said handle 10, to the short arm 13 of which lever is connected the upper and outer end of the piston rod 7 by means of a ball and socket joint 14. The handle 10 extends outwardly laterally at 15 a short distance from the upper end of the pump barrel 2, to a point 16 at which the actuating lever 11 is pivoted at 12, and extends downwardly at 17 from said point at an angle of substantially forty-five degrees with relation to the axis of said pump barrel, in position to be readily gripped by one hand, while the thumb of said hand is applied to the long outer arm 18 of the actuating lever 11.

The valve 3 comprises a cap 19, secured on the lower end of the pump barrel 2, and a flexible rubber valve disc 20 secured at its center to the

2

inner side and at the center of the lower wall 21 said cap, by a rivet 22, over inlet openings 23 in said cap wall, so that said disc normally rests against the inner side of said cap wall and closes said inlet openings.

The piston 6 is threaded on the lower end of the piston rod 7, as indicated at 24, and said piston is provided with ports 25 extending axially therethrough, which ports are opened on the down-stroke and closed on the up-stroke of said piston by a flexible rubber disc valve 26, which is secured at the center thereof to the upper side of the piston 6 by a nut 27 threaded on the piston rod 7 against the upper side of said disc valve 26, which is provided with a central opening 28 through which said piston rod extends. A rubber packing ring 29 is fitted in an annular groove 30 in the periphery of the piston 6 and forms a seal between the piston and the inner side of the pump barrel 2. The lower end of the spring 9 bears against the nut 28.

The pump barrel 2 extends through the bottle cap 5, with the upper wall 31 of the cap formed integral with said barrel at 32. The lower end 15 of the side wall 33 of the cap 5 is formed with an annular internally grooved socket 34 adapted to spring over an annular external bead 35 on the neck 36 of a catsup bottle 37.

The spout 4 extends upwardly and outwardly 30 at an angle from the pump barrel 2 and the upper outer end of said spout is normally closed by a cover 38 which is pivoted at its rear edge at 39 to the rear side of the outer upper edge of said spout, so that said cover swings closed by gravity when 35 my pump is in an upright position, as shown in Fig. 1 of the drawing.

The operation of my invention is as follows:

The pump barrel 2 is introduced into the catsup bottle 37 through the mouth thereof, until the 40 lower end of the barrel rests near the bottom of the bottle and the cap 5 fits over and closes the mouth of the bottle with the annular socket 34 of said cap sprung over the annular bead 35 around the bottle neck 36. A person, desiring to 45 dispense catsup from the bottle 37 for seasoning his food, grasps the angular portion 17 of the handle 10 with one hand, and upon raising the bottle 37 to a position, with the pump spout 4 directed toward said food and the spout 38 swung open by gravity, depresses the arm 13 of the actuating lever 11 with the thumb of his said hand, and then releases said thumb from said lever arm alternately, a sufficient number of times. When 50 said arm 13 of said lever 11 is depressed, as aforesaid, the piston 6 is raised against the tension of

the spring 9, by the short arm 13 of said lever, through the ball and socket joint 14 and the piston rod 7, and the piston valve 26 is closed, so that catsup above the piston 6 is forced by said piston out of the barrel 2 and its spout 4 onto said food, while the inlet valve 3 is opened and catsup is drawn, by the suction of the piston 6, from the bottle 37 through the valve inlets 23 into the lower end of said pump barrel 2. When the arm 18 of the actuating lever 11 is released, as aforesaid, the piston 6 is forced down by the expansion of the spring 9, whereupon the inlet valve 3 is closed by the pressure of the piston 6, while the piston valve 26 is opened by the pressure of the catsup in the barrel 2 below said piston, so that catsup below the piston passes through the piston ports 25 into the barrel 2 above the piston, to be forced out of the barrel and its spout 4 as aforesaid.

The lower end of the barrel 2 may be bent to one side, as indicated in dotted lines in Fig. 1 of the drawing, to position said end of the barrel in the lower corner of the bottle 37 adjacent the under side of the bottle, when the bottle is tipped to one side to direct the spout 4 to a point of delivery of the catsup from the bottle, so that the last small amount of the catsup remaining in the bottle, upon pumping the catsup therefrom, will gravitate toward the lowermost point of the bottle around said lower end of the barrel and be pumped out of the bottle by the pump, thus enabling the pump to pump practically all of the catsup out of the bottle before it is necessary to remove the pump from the bottle to refill the bottle with additional catsup to be dispensed, as above described.

I claim:

1. A dispenser as disclosed including a barrel, an inlet valve in the lower end of said barrel, a spout leading from the upper end of said barrel, a head on the upper end of said barrel, and a handle on the upper end of said barrel, a piston in said barrel, a valve in said piston which opens on the down-stroke of the piston and closes on the up-stroke of the piston, a piston rod extending through said head on the upper end of said barrel, a spring surrounding said piston rod between said piston and said barrel head for nor-

mally holding said piston in its lowermost position, an actuating lever pivoted to said handle above said barrel head and said handle, with one arm of said lever connected to the upper end of said piston rod, and the other arm of said lever in position to be depressed by the thumb of one of the user's hands while said hand holds the dispenser in operative position by said handle.

2. A dispenser as characterized by claim 1 constructed with a bottle cap for closing the mouth of a bottle with the barrel extending through said mouth into said bottle.

3. A dispenser as characterized by claim 1 including a bottle cap secured on the dispenser barrel for closing the mouth of a bottle with the barrel extending through said mouth into said bottle, said cap being formed with means for engaging the bottle to hold said cap in position closing the mouth of the bottle.

4. A dispenser as characterized by claim 1 constructed with a bottle cap for closing the mouth of a bottle with the dispenser barrel extending through said mouth into said bottle, said cap being formed with a socket to be sprung over a bead on said bottle to hold said cap in position closing the mouth of the bottle.
